UNITED STATES PATENT OFFICE.

GILBERT H. BLAKESLEY AND AZEL T. ROBINSON, OF BRISTOL, CONN.

DESIGN FOR CLOCK-CASE SASH.

Specification forming part of Design No. **7,251**, dated March 24, 1874; application filed November 8, 1873.
[Term of Patent 14 years.]

To all whom it may concern:

Be it known that we, GILBERT H. BLAKESLEY and AZEL T. ROBINSON, both of Bristol, in the county of Hartford and State of Connecticut, have invented and produced a Design for a Clock-Case Sash, of which the following is a specification:

The nature of our design is fully represented in the accompanying drawing, to which reference is made.

The lower part of the sash is square and the top is semicircular in form. The sash is formed by a molding, which follows the contour above described and shown, thus leaving the opening C, which is designed to receive the glass, of the same contour as the sash, namely, a square-bottomed and round-topped figure, and a little higher than it is wide.

At the junction of the circular and straight parts of the sash we affix what we term drops or ornaments α α , of any pattern that may be selected.

What we claim as our invention is—

A design for a sash for a clock-case, in which the frame that forms the sash has a right-angled base, parallel sides, and a semicircular top, said sides and top being connected by drops α α , and the opening C inside the sash being of the same form as the contour of the sash, all substantially as shown and described.

GILBERT H. BLAKESLEY.
AZEL T. ROBINSON.
